UNITED STATES PATENT OFFICE

110,660

DESIGN FOR A COAT

Sol Prestyly, Brooklyn, N. Y.

Application June 28, 1938, Serial No. 78,110

Term of patent 3½ years

To all whom it may concern:

Be it known that I, Sol Prestyly, a citizen of the United States of America, residing in Borough of Brooklyn, city of New York, county of Kings, and State of New York, have invented a new, original, and ornamental Design for a Coat, of which the following is a specification, reference being had to the accompanying drawing, forming part thereof.

Fig. 1 is a front view of coat showing my new design.

Fig. 2 is a rear view thereof.

My design is characterized by the specific pockets and collar in association with the specific sleeves as shown.

I claim:

The ornamental design for a coat, substantially as shown and described.

SOL PRESTYLY.
